Fig. 2

INVENTOR:

Gustav J. Gruendler

BY *John H. Kinney*
ATTORNEY.

UNITED STATES PATENT OFFICE.

GUSTAV J. GRUENDLER, OF CLAYTON, MISSOURI.

REFRIGERATOR.

Application filed November 9, 1921. Serial No. 514,006.

To all whom it may concern:

Be it known that I, GUSTAV J. GRUENDLER, a citizen of the United States, residing in Clayton, county of St. Louis, and the State of Missouri, have invented a new and useful Improvement in Refrigerators, of which the following is a full, clear, and exact specification, reference being had to the accompanying drawings, which form a part thereof.

My invention relates to refrigerators and more particularly to refrigerators having an ice container which consists of an upper receptacle having a plurality of downwardly extending legs adapted to be filled with ice.

From practice it has been learned that if the air in a refrigerator be passed over ice the cooling effect of the ice will, to a great extent, purify the foul air sometimes found in refrigerators and will prevent obnoxious odors. Merely passing the air over a block of ice will not suffice to accomplish efficiently the greatest result in purification of the air; and it is preferable to allow the air to circulate around and between small pieces of chipped ice such as are usually placed in the legs of an ice container such as mentioned above.

The objects of my invention are to provide a refrigerator having an ice container so constructed as to effectually purify the air in a refrigerator; to provide in a refrigerator an ice container wherein the air in the refrigerator may circulate around and come in contact with the ice in the container; to provide in a refrigerator means whereby air may enter the ice container thereof and may circulate in all directions around the ice in the container; and to provide in a refrigerator an ice container provided with passages extending from side to side and upwardly from the bottom thereof through which air may pass into or from the upper part of the container and thus be allowed to circulate around and come in contact with the ice in said container.

My invention is fully shown in the accompanying drawings wherein similar letters are used to designate similar parts. Fig. 1 is a perspective view of the ice container of a refrigerator showing how it may be arranged with wheels on its lower sides so as to be slidably mounted on tracks which may be extended from the refrigerator so that the container may be partially removed

therefrom when it is to be charged; Fig. 2 is a view in section showing the ice container in place in the ice chamber of the refrigerator.

Referring to the figures, the ice container of the refrigerator M comprises the upper body portion A adapted to be filled with ice broken in small pieces, in a single large block, or a number of blocks; and having the downwardly extending legs B which are adapted to be filled with chipped or broken ice, preferably small pieces. The ice container may have the wheels C arranged on the shafts D on the lower portion of its sides near the corners thereof, as shown in Fig. 1. The wheels C are, preferably, held on the shafts D by the cotter pins E, but, of course, any other means suitable for the purpose may be used. The wheels C are grooved so as to roll along the tracks F which may be extended, as will be herein-after described, from the refrigerator M wherein the ice container is to be used. If the ice container is mounted on these tracks, as is the preferable construction, when the container is to be charged it is rolled outwardly from the refrigerator along the tracks F and thus partially removed from the refrigerator so as to be quickly and easily filled with ice.

Air passages G open at the bottom and at the top are provided between adjacent legs B, and the walls thereof may be arranged with the flanges H as shown in Fig. 2. The guards J are positioned above the upper end of the passages G to prevent ice from entering said passages; and are, preferably, formed with sloping sides meeting in a peak, as shown in the drawings, and with the downwardly extending flanges at the outer ends of the sides so that when chipped or broken ice is poured into the container onto the guards it will be deflected thereby into the legs and will be prevented from entering the passages G. The guards J are arranged so that a space through which air may pass is left between the under sides thereof and the open tops of the air passages G and are attached at their ends to the walls of the upper receptacle A. In addition the guards may be supported at intervals in any suitable manner on the upper ends of the walls of the passages G. Since the legs B extend downwardly from the upper receptacle A, which is filled or partially filled with ice, the openings be-

tween the guard J and the upper ends of the walls of the air passages G will be positioned so that air from the lower portion of the refrigerator M will be allowed to 5 enter the ice container not only at the top, bottom and sides thereof, but at the middle portion thereof in the midst of the ice, and hence the air may circulate in all directions through the spaces between the pieces of 10 chipped or broken ice surrounding the openings. The lower ends of the legs B are provided with openings, such as the slits K, whereby the water from the melted ice will drain out of the container. The legs B 15 are, preferably, made narrower at the bottom, as shown in Fig. 2, and hence the passages G will be widest at the bottom and tapering in toward the top.

In Fig. 2 the ice container is shown in 20 place in the ice chamber L which has the opening N in the front thereof through which the ice container may be partially removed when it is to be charged. The tracks F are, preferably, positioned above 25 the floor of the ice chamber, as shown, so that the air in the refrigerator will be allowed to circulate underneath the ice container in the ice chamber. The tracks F have the pivotal joint O near the middle 30 thereof so that a portion of the tracks may be swung upwardly inside the opening N in the position shown by the dotted lines in Fig. 2. When the door which is not shown but which normally closes the opening N, 35 is open, the tracks F are swung downwardly to extend outwardly from the refrigerator M so that the ice container may be rolled outwardly thereon and be partially removed from the refrigerator.

40 In use the ice container is filled with chipped or broken ice after being partially removed from the refrigerator M as described, and is then rolled back along the track F into the ice chamber adapted to receive it. Air from the refrigerator will enter the ice chamber L in which the ice container is placed and, since the warm foul air or 45 gases rise, such air will enter the upper part of the ice chamber and will go into the top 50 of the ice container. The air will circulate between the passages of ice in the upper portion and most of the air will pass through the openings in the top of the passages G. Any moisture in the air will be condensed 55 on the metal walls of the passages G. The air or gases by coming in contact with the ice will be purified and cooled, and any condensation therefrom will be drained off with the water from the melted ice, through the slits K in the bottom of the legs B. This 60 circulation of air through the chipped or broken ice will not only purify the air in the refrigerator, but will also greatly increase the efficiency of the refrigerator as 65 a preserving and cooling unit. One of the

novel features of my invention is that the air is not merely allowed to pass over the top of the ice, but is caused to circulate in the midst of the chipped or broken ice in all directions through the container. 70

I do not purpose to limit my invention to the exact constructions of the legs and passages shown in the drawings, since any passages open at the top so that the air may rise upwardly therethrough and be discharged into the ice container would come within the spirit of my invention. 75

What I claim as new and desire to secure by Letters Patent, is:

1. In a refrigerator having an ice chamber, the combination of tracks in said chamber adapted to be made to extend outside thereof, with a metal ice container provided with an upper body portion having a plurality of downwardly projecting legs 80 open at their lower ends and which extend across the bottom of said body thereby providing uninterrupted air passages between said legs across said container, the bottom of said body portion being provided with 85 openings between said legs, the upper and lower ends of the walls of said legs being provided with stiffening flanges, shields whereby ice and water are prevented from passing through said openings between said legs in the bottom of said body portion, and members attached to the lower ends of two or more of said legs adapted to engage with 90 said tracks so as to allow said container to be moved into or out of said chamber on 100 said tracks in a direction substantially longitudinally of said container.

2. In a refrigerator having an ice chamber, the combination of tracks in said chamber adapted to be made to extend outside thereof, with a metal ice container provided with an upper body portion having a plurality of downwardly projecting legs open 105 at their lower ends and which extend in substantially parallel spaced relation across the bottom of said body portion, the bottom of said body portion being above the middle line of said container and being provided with openings between said legs, the upper and lower ends of the walls of said legs 110 being provided with stiffening flanges projecting outwardly, shields whereby ice and water are prevented from passing through said openings between said legs in the bottom of said body portion, and members 115 attached to the lower ends of two or more of said legs adapted to engage with said tracks so as to allow said container to be moved into or out of said chamber on said tracks in a direction substantially longitudinally of said container. 120

In witness whereof I have signed my name to this specification.

GUSTAV J. GRUENDLER.
